FIG. 8.

Inventor

Abraham Susseles,

By his attorney

Edgar Gates Co.

UNITED STATES PATENT OFFICE.

ABRAHAM SUSSELES, OF BROOKLYN, NEW YORK.

MANUFACTURE OF PULL-RINGS, BUCKLES, AND THE LIKE.

1,260,092.

Specification of Letters Patent. Patented Mar. 19, 1918.

Application filed December 10, 1917. Serial No. 206,507.

To all whom it may concern:

Be it known that I, ABRAHAM SUSSELES, a citizen of the United States, and residing at Brooklyn, in the county of Kings and State 5 of New York, have invented certain new and useful Improvements in the Manufacture of Pull-Rings, Buckles, and the like, of which the following is a specification, such as will enable those skilled in the art to which it ap-

10 pertains to make and use the same.

This invention relates to the manufacture of pull rings, buckles or like devices, and particularly to devices of this class having a cover or casing of leather; and the invention 15 consists in the improved method, or process, of forming and applying the cover or casing to the pull ring, buckle or other device hereinafter described and claimed.

The invention is fully disclosed in the following specification, of which the accompanying drawing forms a part, in which the separate parts of my improvement are designated by suitable reference characters in each of the views, and in which:—

25 Fig. 1 is a plan view of a strip of leather which I employ in making the cover or casing of a pull ring or buckle;

Fig. 2 a similar view showing the first step 30 in forming said cover or casing from said strip;

Fig. 3 a transverse section on the line 3—3 of Fig. 2;

Fig. 4 a view similar to Fig. 3 but showing the second step of the process of forming 35 the cover or casing;

Fig. 5 a view similar to Fig. 4 but showing the third step in the process of forming the cover or casing, said figure being also a section on the line 5—5 of Fig. 6;

40 Fig. 6 a view similar to Figs. 1 and 2 but showing the complete cover or casing;

Fig. 7 a view of an open pull ring composed of a heavy wire or rod and showing the beginning of the operation of applying 45 the cover or casing thereto; and,

Fig. 8 a view of the complete pull ring with the cover or casing applied.

In the practice of my invention, I first provide a strip *a* of leather which is of pre- 50 determined width, and said strip may be of the exact length required to form the cover or casing for a pull ring or buckle of predetermined dimensions or said strip may be of any desired length and separate parts or 55 sections may be cut therefrom in forming the desired cover or casing.

The second step in the process of forming the cover or casing from the strip *a* consists in folding the edge portions of said strip inwardly onto the body portion thereof as 60 shown at *a*², and the inwardly folded edge portions *a*² are also of predetermined width and are firmly pressed onto the body portion of the strip and may be sealed, gummed or otherwise secured thereto. 65

The third step in forming the cover or casing consists in folding the strip *a* centrally and longitudinally as shown at *a*³ in Fig. 4, which operation brings the edge folds *a*² together, and the fourth step of the process 70 consists in stitching the folded sides of the strip together longitudinally and through the edge folds *a*² as shown at *a*⁴ in Figs. 5 and 6, and this forms the complete tubular cover or casing *a*⁵ for the pull ring or buckle 75

In the accompanying drawing I have shown in Fig. 7 an open pull ring *b* made of heavy wire or a rod of predetermined transverse dimensions and length, and in forming the pull ring in this manner the 80 ends *b*² and *b*³ are bent inwardly as shown in said figure so that one side of the complete ring is approximately straight, and the opposite side semi-circular or arc-shaped in form, and in the operation of applying the 85 cover or casing one of the ends, the end *b*³, as shown in the drawing, is bent outwardly as shown in said figure, and the cover or casing slipped on over and entirely around the ring, or said ring is worked through or 90 slipped through the cover or casing, after which the end *b*³ is bent back into its proper position, as indicated in Fig. 8, and this forms the complete pull ring *c* shown in said figure, and in the above described operation 95 both end portions of the ring *b* may be bent outwardly, if desired, in the operation of applying the cover or casing, after which both end portions may be bent back into their proper position, or the open ring may first 100 be made in a circular form, or approximately so, and after the cover or casing has been applied both ends of said ring may be bent inwardly, as will be readily understood.

Although I have not shown my improvement applied in the manufacture of buckles, 105 it will be apparent that the bodies of buckles may be made in the same manner as pull rings and that the tongue may be applied in the usual manner, the manufacture of 110 buckles and similar devices and providing leather covers or casings therefor made and

applied in other ways being well known at the present time, as is also the manufacture of pull rings, my invention being limited to the method of forming and applying the 5 cover or casing as herein described.

Although I have described the use of leather in my improved method of making and applying covers or casings for pull rings, buckles and other articles, my invention 10 is not limited to the use of this material and any suitable fabric material may be employed, or fabric material treated to represent leather or what is known as artificial leather, and in doing this, or in making 15 the cover or casing of fabric, said fabric is cut on the bias to form the strip or strips from which the cover or casing is made, the object of this being to allow for the stretching of the material of the cover or casing in 20 the operation of applying it to the pull ring, buckle or other device, or to permit the stretching of the cover or casing in said operation which stretching facilitates the application of the cover or casing to the ring 25 or buckle, or the passing of the ring or buckle through said cover or casing.

Having fully described my invention, what I claim as new and desire to secure by Letters Patent, is:—

30 1. The method of making a cover or casing for an open pull ring, buckle or the like which consists in first providing a strip of flexible material of predetermined width,

then folding the edge portions of said strip inwardly onto the body portion thereof, the 35 folded edge portions being also of predetermined width, then folding said strip centrally and longitudinally so as to bring the folded edge portions thereof together, and then stitching the folded sides of said 40 strip together longitudinally thereof and through the folded edge portions thereof.

2. The method of making and applying a cover or casing to an open pull ring, buckle, or the like which consists in first providing 45 a strip of flexible material of predetermined width, then folding the edge portions of said strip inwardly onto the body portion thereof, the folded edge portions being also of predetermined width, then folding said 50 strip centrally and longitudinally so as to bring the folded edge portions thereof together, then stitching the folded sides of said strip together longitudinally thereof and through the folded edge portions thereof, and then slipping the open ring, buckle 55 or the like through the casing or cover thus formed.

In testimony that I claim the foregoing as my invention I have signed my name in 60 presence of the subscribing witnesses, this 7th day of December, 1917.

ABRAHAM SUSSELES.
